(57) **CLAIM**

The ornamental design for a lighting device, as shown and described.

DESCRIPTION

FIG. 1 is a perspective view of a lighting device showing my new design in a first configuration, as viewed from the top and one side.

FIG. 2 is a first side elevation view of the lighting device of FIG. 1 in the first configuration.

FIG. 3 is a second side elevation view of the lighting device of FIG. 1 in the first configuration.

FIG. 4 is a top plan view of the lighting device of FIG. 1 in the first configuration.

FIG. 5 is a front elevation view of the lighting device of FIG. 1 in the first configuration.

FIG. 6 is a bottom plan view of the lighting device of FIG. 1 in the first configuration.

FIG. 7 is a back elevation view of the lighting device of FIG. 1 in the first configuration.

FIG. 8 is a top plan view of the lighting device of FIG. 1 in a second configuration; and,

FIG. 9 is a bottom plan view of the lighting device of FIG. 1 in the second configuration.

The broken lines shown on the drawings depict portions of the lighting device that form no part of the claimed design.
